LAUNDRY CART

Walter N. Kraus, Colorado Springs, Colo.

Application August 14, 1952, Serial No. 21,043

Term of patent 7 years

(Cl. D14—4)

To all whom it may concern:

Be it known that I, Walter N. Kraus, a citizen of the United States, residing at Colorado Springs, State of Colorado, have invented a new, original, and ornamental Design for Laundry Cart, of which the following is a specification, reference being had to the accompanying drawing, forming a part hereof.

The single figure is a front perspective view of a laundry cart showing my new design;

The side and end of the cart opposite those shown are similar in appearance.

I claim:

The ornamental design for a laundry cart, as shown and described.

WALTER N. KRAUS.
